M. ELMER.
FRANGIBLE SEAL.

APPLICATION FILED MAR. 27, 1918.

1,297,452.

Patented Mar. 18, 1919.

UNITED STATES PATENT OFFICE.

MARTIN ELMER, OF HASTINGS, MICHIGAN.

FRANGIBLE SEAL.

1,297,452.

Specification of Letters Patent. Patented Mar. 18, 1919.

Application filed March 27, 1918. Serial No. 225,100.

To all whom it may concern:

Be it known that I, MARTIN ELMER, a citizen of the United States, residing in the city of Hastings, county of Barry, and State 5 of Michigan, have invented certain new and useful Improvements in Frangible Seals, of which the following is a specification, reference being had to the accompanying drawings, forming a part thereof.

10 The object of this invention is to provide an improved form of self-locking seal of the type in which a flexible strap constitutes the means for engaging the seal with the parts of the device to be sealed by it.

15 In the drawings:

Figure 1 is a side elevation of a seal embodying this invention, showing the seal as applied to the handle and cover of a milk can, the latter part being shown in section.

20 Fig. 2 is a detail section of the seal device taken as indicated at line 2—2 on Fig. 1.

Fig. 3 is a section showing the interior construction of the seal, and being taken as indicated at line 3—3 on Fig. 2.

25 Fig. 4 is a section taken similarly to Fig. 3, but showing the parts with the loop or ribbon member removed, and with the key member in position for receiving the ribbon, instead of locked position, as shown in Fig. 3.

30 Fig. 5 is a dissected view of the shell and parts to be assembled therein, but not including the ribbon itself.

Fig. 6 is a sectional view similar to Fig. 4, but showing a modified form of the invention.

35 Fig. 7 is a sectional view similar to Fig. 3, and showing a further modification of the invention.

Fig. 8 is a detail section taken as indicated 40 at line 8—8 on Fig. 7.

Referring to Fig. 1, it will be seen that the portions of the milk can chosen to illustrate the mode of use of a seal embodying this invention are only indicated by fragments of the handle A, the top flange, B, and the cover, C. The band or ribbon, 1, of the seal is formed in a loop passing around the handle, A, and through apertures, b and c, in the flange and cover respectively; and, since in the usual type of milk can, the removal of the cover involves drawing it for a considerable distance along the common axis of the can and cover, and away from the flange, B, it will be evident 45 that such movement, if checked by the presence of the loop of ribbon 1, could only

be effected after the ribbon had been severed. For clearness of illustration, the ribbon, 1, is shown as arranged to permit considerable play of the cover C, with the loop; but it 60 may be understood that this play is not inherent in the seal itself, and may be entirely eliminated if desired to draw the loop tight about the parts which it engages.

To form a closed loop of the ribbon, 1, 65 its free ends, 2 and 3, are each passed through an aperture in a key member, 4, and folded back over said member, the latter thus forming a link in the loop; and by inclosing the key 4, within a shell, preferably composed 70 of two parts, 5 and 6, whose walls engage and confine the folded ends of the ribbon, said portions of the ribbon are held flat against the key member, 4, and each end portion is folded sharply around the edge of 75 the aperture in the key, through which it passes. The aperture is so shaped that its edge which thus engages the ribbon extends obliquely with respect to the ribbon itself, so that any strong pull upon the ribbon will 80 tend to cut it over this edge of the key aperture. In the form of key illustrated in Figs. 3, 4 and 5, two apertures, 7 and 8, are shown in the key, 4, to receive respectively the end portions, 2 and 3, of the ribbon, 1, while, in 85 the key member shown in Fig. 6, a single aperture, 9, serves the purpose; but in either form the edge of the ribbon, 1, is engaged by an edge of an aperture extending oblique to it, and in both cases illustrated both edges 90 of the ribbon are so engaged by oblique edges of the aperture, so that when the ribbon is placed under excessive tension, the cutting action proceeds simultaneously from both its edges toward the middle of its 95 width, and its cross-section is rapidly reduced insuring breakage or severance. In the forms illustrated the edge of the aperture which actually engages the ribbon is thus V-shaped in outline with the apex 100 pointed outwardly; that is, toward the corresponding end of the member, 4, and in the general direction of the ribbon itself as assembled with such key.

The two parts, 5 and 6, of the shell are 105 shown in Fig. 2 as secured together by crimping or clenching of the flange, 10, of the part 5, over an annular flange, 11, on the part, 6. As thus assembled the flat walls of the shell are separated just sufficiently to 110 admit the thickness of the key member, 4; but each wall is formed with an offset chan-

nel, 12, to accommodate the thickness of the ribbon, 1, as it is folded flat upon each face of the key, 4. The flanges, 10, 11, and the connecting flange forming the side wall of the shell, are apertured at 13 and 14, to permit limited sliding of the key member, 4, through the shell, and a locking spring, comprising yieldable arms, 15, and a cross bar, 16, offset in a plane below the arms, 15, is secured in the shell by engagement of said offset cross bar, 16, in a depression, 17, in the member, 6.

The shell members having been assembled with the spring in this position, the smaller end, 18, of the key member, 4, is inserted first through the aperture, 13, and passed between the arms, 15, of the spring, emerging at the aperture, 14, and being stopped against withdrawal by engagement of the abutments, 19, in its edges with the spring arms, 15, as seen in Fig. 4. A length of ribbon, 1, having been cut off for use, this length may be threaded through the apertures, 13 and 14, prior to insertion of the key, 4, or along with said key member, with the end portion, 2, of the ribbon bent through the aperture, 7, of the key; or, if preferred, since the key member will be retained frictionally in position shown in Fig. 4, the end, 2, of the ribbon, 1, can be inserted through the aperture, 14, after the key, 4, is in position, said end, 2, of the ribbon emerging at aperture, 13, and being then threaded through the aperture, 7, in the key, 35 and re-inserted in aperture, 13, emerging finally at 14, after passing along the channel, 12, in the shell wall. The one end, 2, of the ribbon having been engaged with the key member, 4, in the shell by any of the three foregoing methods, the other end, 3, of the ribbon, is led around or through the parts or apertures of the device which is to be sealed, and threaded through the other aperture, 8, of the key member, 4, which is also exposed while the key remains in position shown in Fig. 4. The key, 4, is then pushed farther into the shell to position for engagement of its abutments, 20; with the ends of the spring arm, 15, whereby it is locked 50 against withdrawal in this position as shown in Fig. 3, and with the apertures, 7 and 8, and bent ends of the ribbon thus entirely within the shell. The key member, 4, is also stopped against further insertion by engagement of its shoulders, 21, with the side wall of the shell at the aperture, 13, the ends of the ribbon being thus confined between the flat walls of the channels, 12, of the shell are kept sharply bent around the edges of apertures, 7 and 8, and will not reeve through said apertures, particularly by reason of the oblique relation of the aperture edges to the edges of the ribbon which cause the latter to be severed upon any excessive tension in the 65 ribbon. These bent portions of the ribbon

thus being entirely confined within the shell, and it being impossible to manipulate them through the apertures in the key member, 4, any elongation of the loop of the ribbon, 1, is thus prevented and the seal effectually retains the sealed parts in the desired relation, and the ribbon must be actually cut or broken to release the parts.

As already noted, Fig. 6 shows a modification in which the two apertures, 7, and 8, are simply merged into a single aperture, 9, in the key member, 4. A further modification is illustrated in Figs. 7 and 8, in which a single aperture, 22, is similarly formed with V-shaped edges pointing to its opposite ends. 75 In this device, however, the locking of the key member, 4, is effected by the engagement of a protuberance or offset, 23, of a spring member engaging directly between the sharply bent portions, 2 and 3, of the ribbon, 1, within the aperture, 22. The offset, 23, is formed in a partially severed diametral strip, 24, of a spring metal disk, 25, lodged in the cavity of the shell, in which clearance is provided for the yielding movement of the strip, 24, and offset, 23, by a channel-shaped offset, 26, in the shell itself. This arrangement for locking the key member, 4, in position dispenses with shoulders or abutments, 19, 20 and 21, but requires the 90 entering end of the key member to be beveled as shown at 27, to facilitate its entry past the spring abutment, 23. Because of the position of the spring abutment, 23, in relation to the key member, 4, after insertion of the latter, it will be evident that the end, 2, of the ribbon, 1, will be first threaded through the shell and through the aperture, 22, of the key, before said key is introduced into the shell. From this point, however, the 100 completion of the sealing operation is the same as for the other form, that is, the remaining end, 3, of the ribbon, 1, is inserted in the aperture, 22, before said aperture is moved within the shell, and then, upon sliding of the key member, 4, to carry the aperture within the shell, the final lock is effected by engagement of the spring abutment, 23, in the aperture, 22, and between said end portions, 2 and 3, of the ribbon, 1. 105

It will be evident that many further modifications of form may be made without departing from the spirit of my invention.

I claim:

1. A sealing device comprising a casing, 120 a key, and a flat sealing strap; the casing having an aperture in which the key fits for longitudinal thrust thereinto with clearance at opposite sides for the flat strap, the key having an aperture whose edge is angular, 125 one end of the strap being inserted through the aperture, the casing aperture being adequate only to accommodate the key and the strap when the latter is folded close against the opposite sides of the key, and means for 130

- engaging the key with the casing when the key is thrust in the casing far enough to carry the fold of the strap on the edge of the key aperture into the casing.
- 5 2. In the sealing device defined in claim 1, means for securing the other end of the strap to the casing consisting of an aperture in the key through which said end of the strap is entered from one side and folded against 10 the opposite side of the key before the key is thrust to locking position in the casing.
- 10 3. In the sealing device defined in claim 1, the aperture in the key with which the strap end is engaged having an edge over which 15 the strap is bent for such engagement, sloped obliquely away from the fold or bend of the strap which is lodged upon it for severing the strap by a draw cut when the latter is pulled against such obliquely sloping edge.
- 20 4. In the sealing device defined in claim 1 foregoing, the side of the aperture in the key with which the strap end is engaged, comprising edges which are at an angle to each other sloping away from the fold of the 25 strap at the opposite lateral edges of the latter, convergingly toward the middle of the width of the strap; whereby the strap is supported only at its lateral edges on said sloping edges of the aperture for a draw cut 30 inward from both of said edges of the key aperture when the strap is pulled against it.
5. In the sealing device defined in claim 1, the other end of the strap being secured to the key at a point in the length of the key 35 which is within the casing at the locked position of the key, the strap extending from its said securement out in the direction in which the key is thrust into the casing for carrying into the casing the fold of the first 40 mentioned end of the strap.
6. In the sealing device defined in claim 1, both ends of the strap being engaged in the same aperture of the key, the strap running in opposite directions from said engagements for emerging from the casing in opposite directions, one of said directions being that in which the key is thrust into the casing for carrying in the fold of the first 45 mentioned end of the strap.
- 50 7. In the sealing device defined in claim 1, both ends of the strap being engaged with the key and running in opposite directions

from their engagement for emerging from the casing; means for locking the key in the casing, consisting of an offset projecting into 55 the cavity of the casing for engaging between the two end portions of the strap at their folds respectively around the aperture edges of the key with which they respectively engage.

60 8. A seal comprising a shell, an apertured key member slidably carried thereby with its aperture initially exposed outside the shell, a band or strap having one end dimensioned for insertion in the exposed key aperture, the shell walls being closely adjacent the key member for bending the band against it and confining said band at the bend when the apertured portion of the key is moved in the shell, and a spring catch device within 70 the shell for opposing the withdrawal of said key after sliding of its apertured portion in the shell.

9. A seal comprising a shell, a flat apertured key member and a flat strap inserted 75 through the key aperture, and bent flatly against the sides of the key, said shell having an opening to admit the apertured portion of the key, and the shell wall adjacent to such opening being formed by the channel which is in cross section substantially equal to that of the strap, to accommodate and confine said strap to the key, together with means for locking the key against withdrawal of its apertured portion from the 80 shell.

10. A seal comprising a shell, an apertured member slidably carried thereby, and a pliable strap formed in a loop with its ends bent back upon themselves forming oppositely-directed hooks both engaging the apertured member, the aperture edges thereof being oblique to the edges of the strap, and converging in pairs toward the longitudinal center line of said strap and away 95 from the proximate hooked ends, respectively, together with means for locking the apertured member in position to secure the hooked end inside the shell.

In testimony whereof, I have hereunto set 100 my hand at Hastings, Michigan, this 23rd day of March, 1918.

MARTIN ELMER.
